UNITED STATES PATENT OFFICE

JULIUS MATTER, OF LAACKEN, NEAR BARMEN, GERMANY.

APPARATUS FOR REMOVING LYE FROM FABRICS.

1,037,280.

Specification of Letters Patent. Patented Sept. 3, 1912.

Application filed October 26, 1908. Serial No. 459,591.

To all whom it may concern:

Be it known that I, JULIUS MATTER, residing at Laacken, near the city of Barmen, Rhenish Prussia, Germany, a citizen of 5 Switzerland, have invented a new and useful Improvement in Apparatus for Removing Lye from Fabrics, of which the following is a specification.

The object of the present invention is an 10 apparatus for lixiviating textile materials impregnated with lye in the mercerizing process and recovering the lye. It permits of a rapid and energetic washing out or lixiviation of the goods combined with their 15 very careful treatment. This object is essentially obtained by the goods being repeatedly treated alternately with the washing fluid flowing in counter current through the washing apparatus and with 20 a steaming arrangement. The goods thoroughly heated in the steaming apparatus produce in the cold washing fluid an energetic circulation of the fluid favoring the rapid and complete washing, while the goods 25 cooled in the washing fluid condense a large amount of steam thereon, whereby a further great dilution of the fluid in the goods to be washed out is effected. On the other hand it is possible to obtain practically all 30 the lye ready for immediate use without regeneration, so that hardly any loss arises therein. Besides this the new process offers the advantage that lye is obtained in various desired degrees of concentration which can 35 be used for bleaching, mercerizing and other purposes.

To carry out the process the apparatus shown as an example in vertical section on the drawing is used, the arrangement being 40 as follows:

a is a chamber, on the floor of which is arranged a suitable vat b, which is subdivided by means of vertical partitions c into a number of separate compartments d, d¹, d², 45 etc. Into these separate compartments d dip partitions e which are at such a distance from the partitions c and from the bottom of the compartments d, d¹, etc., that the separate compartments d, d¹ communicate 50 with each other, and a fluid, for example, is able to flow downward from the topmost compartment d² in the form of a cascade. In these compartments d, d¹ are arranged rolls f, f¹, etc., and between them in the upper 55 part of the chamber a are rolls g, actuated by wheels h. The said wheels are

driven by a belt k from a pulley i to the pulley m, or by any suitable driving gear. On the axis of the pulley i is arranged a cylinder n, above which is a cylinder o. In 60 the chamber vertical partitions p, q are arranged for the purpose of obtaining a space to which the entry of the atmospheric air is prevented. For this purpose, the plates p, q dip into the liquid contained in 65 the compartments d, d² and they carry channels r filled with liquid into which drops a cover s, so that by this hydraulic joint an air tight space inside the chamber a is obtained. 70

The roll of material coming from the mercerizing machine is carried over a cylinder u into the compartment d, then upward over the rollers g downward into the next compartment d¹ and so on in a zigzag manner, 75 until the material passes out of the chamber a between the squeezing rolls n, o, ready to be taken where required for further treatment. Inside this air-tight chamber a the removing of the lye from the material takes 80 place. For this purpose pipes v are fitted across the chamber a in such manner that the roll of material in its passage touches these pipes, while above the pipes v and on the opposite side of the material rods w are 85 arranged. The position of v and w with regard to each other is such that the material is stretched between them.

The pipes v are perforated on the side toward the material and steam or another 90 medium is led into the pipes, passing out through the holes and acting on the material carried past, in such manner that the lye is removed from the fiber. The rod w serves to strip off the lye collected on the 95 surface of the material by the blast action of the pipe v, so that it falls down into the compartments d. This action takes place with each pipe v and each rod w, once on the inside of the material and next on the other 100 side, and the lye so driven out of the material falls down into the corresponding compartment d underneath and in this manner a complete removal of the lye from the material gradually takes place, until finally 105 the material passes out, almost entirely free of lye, through the rolls n, o. To obtain a better action the holes in the pipes are distributed so that the whole width of the surface of the pipes is covered and every fiber 110 is subjected to the action of the steam. Before reaching the rolls it is subjected to a

powerful water spray which is supplied through a pipe z . This water flows in to the compartment d^6 and mixes therein with the lye there present and this mixed liquid flows into the following compartment d^5 , from which the other compartments d are supplied. As now the length of material dried in the steam space dips again into this liquid, the liquid in each compartment is continuously raised thereby, and again separated by the pipes v and stripped off by the rods w . Consequently in each compartment, beginning with d , weaker lye will be found, the concentration of which can be regulated at will by the amount of water passing through z . Means are thus provided for regulating the concentration of the lye to any desired degree. The lye always passing from underneath into the compartments d a good circulation is effected.

An important advantage of the new process consists in the circumstance that the lye can be drawn off for direct use from a specific compartment without its having to be regenerated. This advantage is obtained by the chamber a being by means of the described hydraulic or other similar joint inclosed in an air-tight manner in the chamber a so that the entry of carbonic acid thereto is prevented. In the presence of carbonic acid the sodium hydrate is changed according to the equation

that is into sodium carbonate and water. The sodium carbonate could not be used until first regenerated, while it is possible by

means of the present process and the present apparatus to draw off direct from a specific compartment lye of the desired concentration, so that for instance it is possible to take lye for bleaching from the compartment d^3 and from the compartment d or d^1 , into which in this case the partition q would dip, a higher lye for mercerizing purposes, as the separated lye is of course stronger at first and falls gradually with the zigzag travel of the material.

For drawing off the desired lye the compartments may be provided with any suitable means as for instance valves or the like.

What I claim and desire to secure by Letters Patent is:

An apparatus for lixiviating textile materials impregnated with lye comprising an air tight chamber, a number of guiding rolls located in the top of the apparatus, means to revolve said rolls, a corresponding number of rolls arranged on the bottom, both sets of rolls traveling the textile material in zigzag way, a steaming appliance situated on one side of each lap of the material and a stripping off appliance on the other side and delivery rolls placed outside the apparatus, a number of compartments on the bottom of the apparatus arranged in a slanted direction each compartment receiving a guiding roll, and partitions dipping in the compartments as described and for the purpose set forth.
